UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

DETACHABLE SLIDING HANGER FOR SPRING BEDS.

Application filed August 30, 1924. Serial No. 735,175.

To all whom it may concern:

Be it known that I, WILLIAM B. FOSTER, a citizen of the United States, and a resident of Utica, in the county of Oneida and State of New York, have invented certain new and useful Improvements in Detachable Sliding Hangers for Spring Beds; and I do hereby declare that the following is a full, clear, and exact description thereof, which will enable others skilled in the art to which it appertains to make and use the same, reference being had to the accompanying drawings, and to the reference numerals marked thereon which form part of this specification.

My present invention relates to devices usually called hangers which are used to hang or suspend a bedspring within a bedstead. The purpose of my invention is to provide an improved device of this sort and one which is simple in construction and operation and economical in production.

A further purpose is to provide a bedspring hanger which is readily removable or attachable to the bedspring and further to have said hangers slidingly mounted upon the bedspring so that they are adjustable to various combinations of sizes of bedsteads and bedsprings.

Another object is to provide such a removable and adjustable bedspring hanger which can be readily formed from a single length of resilient wire or metal rod.

Fig. 1 is a side elevation and Fig. 2 a plan view of a hanger embodying my invention illustrated in connection with the adjacent parts of a bedstead and a bedspring frame.

Fig. 3 is an end view of said hanger and adjacent parts as seen from the outer end of the hanger and Fig. 4 is a similar view of the same parts as seen from the inner end of the hanger.

Fig. 5 is an end view of said hanger with the adjacent part of the bedspring frame as seen from the inner end of the hanger but with the hanger struck apart at its inner end as is done for assembling the hanger upon the bedspring or removing it therefrom.

In the drawings the bedstead is represented by an angle bar 8 which may be either the side bar or the head or foot bar of a bedstead. As shown in the drawings this bedstead bar 8 is illustrated with its horizon-

tal web above the vertical web but it will be noticed that the hanger herein described is applicable for use when the rail is reversed, that is when the vertical web is above the horizontal web. It will also be seen that the form of my hanger is usable with other forms of bedstead side or head and foot rails. The bedspring frame is formed of the necessary number of cross bars 9 and edge members 10 formed of strips of metal arranged vertically with the bent ends of the cross bars secured in any desired way to the edge members 10. The hanger herein shown is particularly applicable where the cross bars 9 are simply flat strips of metal arranged vertically but the hanger it will be seen is equally usable with any form of edge member for the bedspring such as an angle bar arranged in any form.

The hanger is formed of a single length of sufficiently resilient metal of the proper strength such as large wire or small rod. The length of metal is formed into a relatively long open loop with the free ends of the metal at the inner end of the loop and with said loop as seen from above having a rectangular shape.

The outer portion of the hanger forms the bedstead engaging hook 11. This hook has two horizontal portions 12 one from each leg of the loop adapted to rest upon the side rail 8. From the outer end of each of these horizontal portions the hook extends downwardly as at portion 13 and is at the lower end thereof connected by a horizontal portion 14, the two portions 13 and the portion 14 being at the outside of the side rail and obviously operating to prevent the hanger from sliding inwardly from the rail of the bedstead. From the inner ends of the horizontal portions 12 there extends downwardly the two portions 15 which form arms engaging the inner side of the bedstead member 8 and also lead to the intermediate long horizontal portions 16 which pass below the edge member 10 of the bedspring and are directly engaged by the lower edge of said member 10. From the inner ends of these long arms 16 the metal of each leg of the loop is bent upwardly and towards each other forming the inclined upwardly extending but downwardly opening hooks 17 and 18.

The hangers are readily mounted upon the bed spring frame and particularly upon

the cross bars 9 thereof by springing the two long arms 16 of the hangers apart until the normally over-lapping hooks 17 and 18 are separated as shown in Fig. 5; then the 5 inner or hooked ends of the hanger are passed up from below over the cross bar 9 on opposite sides thereof and then the hanger is allowed to spring back to normal position with its hooks 17 and 18 in over-lapping relation; then the hooks 17 and 18 will engage the upper edge of the cross bar 9 while the arms 16 will pass below the edge member 10 of the bed spring while the outer portion of the hanger, that is the bedstead 10 15 20 25 engaging hook 11, will rest upon the bedstead side rail 8 and be kept from disengagement therefrom by the parts 13 and 15 on the outer and inner side of said rail respectively. It will be noticed that this hanger allows a large range of adjustment in that the hangers can be moved somewhat farther in upon the bed spring than is shown in Fig. 1 or may be moved considerably farther out than is shown in said Figure 1.

These hangers are particularly convenient in that for storage or shipment they can be housed within the outline of the bed spring by simply sliding the hooked ends 17 and 18 30 35 farther in upon the cross bar 9 while the bedstead engaging portion 16 will be inside the edge bar 10 with the parts 12 on opposite sides of the cross bar 9. The portions 13 are long enough to allow the hanger to well over-lap the cross piece 9.

The hangers may be readily detached from the bed spring by any one without the use of special tools by simply raising the hooked ends 17 and 18 above the cross bar 40 45 50 55 60 65 70 75 9 and then spreading the arm 16 of the

hanger apart until hooks 17 and 18 are clear of each other whereupon the hanger may be moved downwardly with the hooks 17 and 18 passing on opposite sides of the cross piece 9.

45

What I claim as new and desire to secure by Letters Patent is:

1. The combination with a bedstead and a bedspring frame having edge members and cross members of hangers formed of lengths of resilient metal rod bent into a long open loop with the sides thereof spaced apart and with the free ends of the rod at the inner end of the hanger and formed into upwardly-extending downwardly opening hooks normally passing each other over the top of a cross member but adapted to be sprung apart for removal or assembling of the hanger, the outer end of the loop being formed into a downwardly opening hook to engage the bedstead and the intermediate part of the hanger engaging the lower face of the edge member.

2. In a bed, the combination of a bedstead, a bed-spring adapted to be hung within the bedstead and having a frame including edge members and cross bars, and hangers each having a bedstead-engaging hook at its outer end, two spaced resilient side members extending inwardly therefrom beneath the edge member of the bedspring frame and at the inner end upwardly-extending downwardly-opening hooks normally passing each other over the top of a cross bar but adapted to be sprung apart for removal and assembling of the hangers.

In witness whereof I have affixed my signature, this 30th day of July, 1924.

WILLIAM B. FOSTER.
